CLAIM

The ornamental design for a canoe/kayak carrier, as shown and described.

DESCRIPTION

FIG. 1 is a perspective view of a canoe/kayak carrier showing my new design;
FIG. 2 is a top plan view thereof;
FIG. 3 is a bottom plan view thereof;
FIG. 4 is a side view thereof, the other side being substantially identical;
FIG. 5 is an end view thereof; and,
FIG. 6 is an opposite end view thereof.
